UNITED STATES PATENT OFFICE.

CHARLES W. KING, OF NEWTON, MASSACHUSETTS, ASSIGNOR, BY MESNE ASSIGNMENTS, TO THE PURITAN LASTING MACHINE COMPANY, OF PORTLAND, MAINE.

MACHINE FOR ASSEMBLING INNER SOLES, UPPERS, LININGS, AND COUNTERS OF BOOTS OR SHOES.

SPECIFICATION forming part of Letters Patent No. 672,624, dated April 23, 1901.

Application filed October 25, 1894. Serial No. 526,974. (No model.)

To all whom it may concern:

Be it known that I, CHARLES W. KING, of Newton, in the county of Middlesex and State of Massachusetts, have invented certain new and useful Improvements in Machines for Assembling Inner Soles, Uppers, Linings, and Counters of Boots or Shoes, of which the following is a full, clear, and exact description.

This invention has for its object the assembling or placing together in proper position of an inner sole, lining, and counter in connection with the upper of a boot or shoe for the lasting of the upper; and the invention consists of the construction and arrangement of parts for the assembling of an inner sole, lining, and counter in connection with the upper of a boot or shoe for the lasting of the upper of the boot or shoe, all substantially as hereinafter fully described, reference being had to the accompanying sheets of drawings, in which is illustrated a machine constructed in accordance with this invention, in which—

Figure 1 is a front elevation. Fig. 2 is a side elevation of the upper part of the machine. Fig. 3 is a plan view. Fig. 4 is a vertical cross-section on line 4 4, Fig. 3. Fig. 5 is a vertical cross-section on line 5 5, Fig. 3. Figs. 6 and 7 are detail vertical cross-sections on line 6 6, Fig. 3, but showing the parts in different positions. Figs. 8, 9, 10, and 11 are plan views showing the several steps taken in using the machine in assembling the parts previous to lasting the upper of a boot or shoe. Fig. 12 is a detail cross-section on line 12 12, Fig. 1. Fig. 13 is a detail vertical section on line 13 13, Fig. 1. Fig. 14 is a plan view similar to Fig. 10, to be hereinafter referred to. Fig. 15 is a detail cross-section on line 15 15, Fig. 14. Fig. 16 is a detail plan view of parts shown in Fig. 14, showing other parts. Fig. 17 is a detail plan view similar to Fig. 11.

In the drawings, A represents a standard or column having a base B, on which are supported and carried the various operating parts of the machine. On the upper end of the standard A is a horizontal plate C, secured by two screws D, which pass down and screw into the standard at a, as shown in Figs. 3 and 4 more particularly. The edges b of this

plate C are shaped to conform generally to 50 the shape or edge of the heel portion of an inner sole, as shown in plan in Fig. 3, and the standard for a short distance below the plate is on the outside shaped correspondingly. Under the plate C is a recess or chamber E 55 between it and the portion a, formed by the walls F, and in this chamber is a horizontal plate G, arranged to freely fit inside the walls and be moved up and down therein, being secured by a central screw d on the upper end 60 of a spindle H, which passes freely down through a vertical passage e in the transverse thickness a of the standard, its lower end extending into a chamber J below in the column, open to the front and connected by a 65 pin f to a link K, pivoted by its lower end g to an arm h of a lever L, pivoted to a cross pin or screw m in the standard, and having a handle M extending out through the front opening of the chamber J for operation thereof. Swinging the lever L down, the plate G, by the link K connection, (which, with the lever-arm h, makes practically a toggle-joint,) is moved up, as shown in Fig. 7 in section, and swinging the lever up the plate is moved down 70 to its normal position, as shown in the other views.

Secured in the plate G at certain distances apart along or near its curved edge are a series of vertical pins N, their upper ends 80 sharpened, of a length when the plate is in its normal position, as shown in section in Figs. 4 and 6 and in plan in Fig. 3, to project up into openings n, vertically coincident therewith, in the fixed plate C near its edge, 85 and when this plate G is moved up into the position shown in section in Fig. 7 the pins will project above the plate, as shown.

P is an arm at the side of the standard extending through an opening r in the side into 90 the chamber J of the standard and pivoted to a cross pin or screw t and at its upper end having a right-angularly-projecting arm u, terminating in a cross-plate R of substantially the same outline as the plate C on the 95 upper end of the standard and preferably a little larger. This arm P is secured to its pivot by a block S, through which the pin t

extends, this block fitting freely in a side opening v in the arm and adapted to slide back and forth therein and having a pin w , which projects up into a socket y in the arm, 5 in which it can freely move back and forth, a spring z in said socket bearing against the upper end of said pin and against the inner end of a screw T , which screws into the arm above said pin, as shown more particularly 10 in Fig. 5.

The inner end of the arm P has on its edge a segment-gear U , concentric to the pin t , which on its upper portion extends in a straight or vertical line, as at a' , Fig. 5, which 15 gear is arranged to engage with a vertical rack-bar V , adapted to slide up and down in a guideway b' in the inside of the column and having a right-angular projecting portion W at its lower end, to which portion is pivoted 20 at d' a pitman-rod Y , connected at its lower end by a pivot c' to a treadle A' , pivoted at e' to the standard and extending forward to and outside of the column for operation thereof by the foot.

25 B' is a spiral spring in the chamber of the column, connected by one end to the treadle at f' and by its other end at g' to the lower end of the rack-bar V , as shown in Fig. 1 more particularly.

30 Pressing down the treadle A' pulls down the rack-bar V , which by its engagement with the segment-gear on the arm P swings the arm forward and toward the standard into a vertical position for its plate R then to be 35 vertically over and a little above the plate C on the upper end of the column, and at such time the rack-bar engages with the gear-teeth on the straight portion a' above the segment portion, so that in the continued downward 40 movement of the treadle and the rack-bar the arm P is pulled down with it until its plate R is close to or bears upon the column-plate, as desired for the purpose of this invention. The downward movement of the arm is against the 45 spring z , the arm sliding or moving over its pivot-block S . The treadle being allowed to rise, the rack-bar moves up, carrying with it the arm P , assisted by its springs z and B' , and as the rack-bar engages with the segmental gear in its continued upward movement it swings the arm P outward into its 50 normal position, as shown in Figs. 1, 3, and 5. On the side of the column next to the arm P are two horizontal lugs h' , between which the 55 arm moves when it is swung up, and in each of these lugs on its outer side is a vertical groove or slot m' at right angles to the movement of the arm, into which move the respective ends or edges n' of a plate C' , secured 60 by screws r' to the inner side of the arm.

When the arm moves down after being swung forward, its plate C' enters the grooves and serves the purpose of steadyng the arm in its downward movement and insuring that 65 its plate R is in the proper position over the column-plate C . Each lug h' is cut away at l' on its outer side to allow in the swing of

the arm forward room for the plate ends n' to pass up into position over the slots or grooves. Above these lugs h' are two horizontal projecting pins u' , which are secured to the standard and are of a distance apart equal to the width of the plate-arm P , between which the arm passes when swung up into position, which pins also serve as guides or steadyng-pins to the arm in its downward movement. Through the arm-plate R are a series of holes or openings v' near its edge, which when the arm is swung up into its true vertical position are over the holes in the 80 plate C , so that with the arm-plate in position over the column-plate if then the pin-plate G is moved up the pins N , passed through the plates C , will also enter more or less the openings or holes v' in the arm-plate. In this 85 way the holes v' serve as a means to receive the pins N .

D' is an arm on the opposite side of the column to the lever L and at right angles to the plate-arm P , pivoted in the side of the standard to a cross pin or screw E' , and in an angular extension w' of this arm is a slot F' , in which is disposed a cross-pin G' of two arms H' , pivoted at y' between two lugs a^2 on the outside of the column and having a handle 95 b^2 for operation thereof. The lugs a^2 are of a block Q , secured to the standard by the pivot-screw t of the arm P passing through a vertical slot d^2 in the block, the block resting on a vertical screw e^2 , screwing up through 100 a lug f^2 of the standard, by which the height of the lugs can be adjusted to regulate the height of the arm D' for its work. Attached to the upper end of this arm D' are two arms J' , projecting forward, having their inner 105 edges curved, as shown in Figs. 3, 10, and 11, and pivoted at g^2 to each end of each of these arms J' are extensions or pieces K' , which project still farther forward and are adapted to freely swing to and from each other on 110 their respective pivots. To press them forward toward each other, each arm K' has a spring h^2 , which bears against its outer side and is coiled around its pivot g^2 , its other end bearing or connected to a pin m^2 on the arms J' . 115 Connected to each outer end of each of these arms by a pivot L' is a chain or flexible band M' , which extends back and is freely disposed in between the arms K' and J' , as shown in plan view in Figs. 10 and 11 more particularly. 120 Attached to each end of the chain is a strip N' of leather, which extends along the inner side of the chain, as shown. Swinging forward the handle b^2 by its slot F' , connected with the arm D' , the arm is swung up until 125 its curved arms J' are in a horizontal position, and in such position they embrace the standard just below the plate C , as shown in dotted lines in Fig. 2 and in Figs. 10 and 11, and when in such position the arm is locked by the cross-pin G' of the handle being at the outer end of the slot F' , and the parts then being substantially at right angles to their pivots it causes 130 a lock of the several parts, which prevents

their movements in themselves; but by operating the handle all parts are moved back to their normal position again.

The operation of the machine is substantially as follows, and is illustrated fully in Figs. 8, 9, 10, and 11: With the machine in its normal position, as shown in Figs. 1, 2, 3, 4, 5, and 6, place the upper P', with its lining Q' inside, over the upper end of the column 10 and let it rest. Then place the inner sole R' by its heel portion on top of the plate C, which supports the same, as shown in Fig. 8, and press down the treadle A', which pulls down the rack-bar V, swinging the arm P forward 15 until its plate R is over the plate C and inner sole, and in the continued movement of the treadle the arm and its plate are pulled down for its plate to press firmly down upon the heel of the inner sole upon the plate C, when the 20 handle M of the lever L is pressed down, which forces the pins N up through the inner sole, as shown in Fig. 8, the arm-plate holding the inner sole down for such purpose. When thus through the inner sole, release the treadle and allow it to rise, when the arm P is 25 swung back, as described, out of the way into position shown in Figs. 1 and 5. The lining Q' at its edges at the heel is then pulled by hand over the edge of the inner sole at the 30 heel and pressed down over the upwardly-projecting pins, as shown in Fig. 9. The heel-counter S' is then placed over the inner sole and the lining thereon, with its sides or edges inserted between the lining and upper and 35 the bottom pressed down close to the lining. Then move the handle b² back, which swings up the arm D' and presses closely the flexible band M' around, about, and against the sides and back of the upper at the heel, which holds 40 the upper, lining, and counter firmly between the flexible band and standard, and when so held swing up the lever L, which pulls the pins N down out from and clear of the inner sole, with the upper, lining, and counter held, as 45 described, by the flexible band. Holding the corners n² of the counter S' by the left hand close down upon the inner sole and its sides against the column, a tack r² is driven through each corner of the counter into the lining and 50 inner sole, as shown in Fig. 10, which secures them together at such points. The upper and parts connected thereto can then be removed from the machine, being ready for lasting. If desired, before the upper is removed from 55 the machine and before securing the counter by the tacks the upper can be brought by the fingers over the counter at its corners and tacks t² driven through it, the counter, lining, and inner sole at the corners of the counter, 60 as before, as shown in Fig. 11, which might be desired for some lasting-machines, although generally it is sufficient to secure the counter to the inner sole without the upper. In front of the standard is a screw T', which screws 65 through its wall and extends into a longitudinal groove u² in the back of the rack-bar to bear against the rack-bar, by which it can be

adjusted as to its close engagement with the arm-gear as desired.

In Fig. 14 is shown in plan a view of the 70 upper end of the arm D', showing the curved arms J' with the arm extensions K' pivoted thereto, with the chain M'; but in this figure each spring h² is constructed of a flat piece of metal fastened, respectively, by screws a² 75 to the outer side of each arm J' and extended forward and bearing against the outer edge of the pivoted arms K'. To the pivot L' of each arm K' is pivoted a plate A² by its tongue-piece b², through which the pin L' passes (see 80 Fig. 15) and on which it can swivel or rock horizontally, the outer surface B² of this plate being curved, as shown in Fig. 14. As the arm D' is swung up for its arms J' to operate upon the parts the plates A² move along the 85 side of the upper, bearing upon the upper and counter at the edge of the inner sole and force the sides of the upper, counter, and lining forward along the edge of the inner sole from the back of the heel, following the curvature 90 of the edge of the inner sole, for as the arms J' move forward the springs h² press the plates A² firmly against the upper in their forward movement, and by the swiveling and rocking motion of the plates their curved bearing-surfaces closely follow the curvature of the edge of the heel of the inner sole, thus bringing all parts to closely conform thereto. It is desirable to sometime press the central seam at the heel of the upper, and in such 100 case a block C² is provided, pivoted, as shown at d², to the arm D', as shown in Fig. 17, the block having a spring e² adapted to bear down upon it and hold it down, the block extending forward, and when the upper, &c., are in 105 the machine the block will press firmly down upon the upper at and over the seam, the block having a V-shaped opening D² in its free end to allow for a tack to be driven through the upper at the seam into the inner sole. In 110 the use of this block as the block is forced forward over the upper it presses the upper at the seam forward over the inner sole and causes it to lay smoothly thereon preparatory to tacking the same. Sometimes it might be 115 desirable to have more than one plate or block A² pivoted to each pivoted arm J', and such is shown in Fig. 16 in plan, in which E² represents two extra plates similar to the plates A², pivoted to the inner ends of the arm J' and arranged to swing thereon in a similar manner to the plates at the outer ends. If desired, 120 more plates could be used; but in such case they would be somewhat shorter.

It is desired for this invention to have the 125 plate C so it will support the inner sole, &c., and yet have openings through it for the pins N of plate G to pass through, as described, to secure the lining temporarily. Therefore these openings can be of any size desired and more 130 or less in number and at any desired place in the plate, although preferably at or near the edge, as shown, and it is preferable that the holes should only be of a size to allow the

pins freely to pass through them; also, a more or less number of pins can be used, the holes corresponding to the number of pins.

If desired, when the inner sole, counter, 5 upper, and lining are held by the flexible band they can be secured by tacks all around the heel, practically lasting the same at the heel.

I have shown the arm R provided with a series of holes corresponding in number to the 10 pins N, as I consider this the preferable construction; but I do not desire to be understood as limiting my invention to this precise construction and arrangement.

I do not lay claim herein to the method or 15 process of assembling the inner sole, lining, counter, and upper of a boot or shoe herein disclosed, inasmuch as the same is made the subject of claim in a divisional application filed April 5, 1901, Serial No. 54,405.

20 Having thus described my invention, what I claim is—

1. In combination, a standard, a plate on the upper end of said standard, a series of holes or openings therethrough, an arm pivoted to said standard having a plate on its upper end, a series of holes in said arm-plate adapted to be coincident with the holes in said first plate when the arm-plate is thereover, a series of pins adapted to be projected 25 through said holes, and a treadle connected to said arm for operation thereof.

2. In combination, a standard, a plate on the upper end of said standard, a series of holes or openings therethrough, an arm pivoted to said standard having a plate adapted to be coincident with the holes in said first plate when the arm-plate is thereover, means for operating said arm, a plate or block arranged to move in a suitable guideway to and 30 from said standard-plate, pins secured to said plate or block, arranged to extend respectively into and through said holes or openings in said standard-plate, and means for operating said pin-plate.

45 3. In combination, a standard, a plate on the upper end of said standard, a series of holes or openings therethrough, an arm pivoted to said standard having a plate on its upper end, a series of holes in said arm-plate adapted to be coincident with the holes in said first plate when the arm-plate is thereover, means for operating said arm, a plate or block arranged to move in a suitable guideway, to and from said standard-plate, pins secured to 50 said plate or block arranged to extend respectively into and through said holes or openings in said standard-plate, and a toggle-lever connected to said pin-plate for operation thereof.

60 4. In combination, a standard, a plate on the upper end of said standard, a series of holes or openings therethrough, an arm pivoted to said standard, having a plate on its upper end, a series of holes in said arm-plate, adapted to be coincident with the holes in said first plate when the arm-plate is thereover, a 65 block in which the arm-pivot is disposed pro-

vided with a pin adapted to move back and forth in said arm, a spring adapted to bear upon said block, a segment-gear on the end 70 of said arm and a straight or vertical extension or continuation of said gear, a rack-bar adapted to engage with said gear, a treadle connected to the rack-bar and a spring connected to the treadle and rack-bar. 75

5. In combination, a standard, a plate on the upper end of said standard, a series of holes or openings therethrough, an arm pivoted to said standard having a plate on its upper end, a series of holes in said arm-plate 80 adapted to be coincident with the holes in said first plate when the arm-plate is thereover, a block in which the arm-pivot is disposed provided with a pin, adapted to move back and forth in said arm, a spring adapted 85 to bear upon said block, and means connected to said arm to swing it on its pivot and pull or move it down.

6. In combination, a standard, a plate on the upper end of said standard, a series of 90 holes or openings therethrough, an arm pivoted to said standard having a plate on its upper end, a series of holes in said arm-plate adapted to be coincident with the holes in said first plate when the arm-plate is thereover, means connected to said arm to swing 95 it on its pivot and then pull it down, slots or grooves in said standard and a plate on said arm to engage with said slots or grooves.

7. In combination, a standard, a plate on 100 the upper end of said standard, a series of holes or openings therethrough, an arm pivoted to said standard having a plate on its upper end, a series of holes in said arm-plate adapted to be coincident with the holes in 105 said first plate when the arm-plate is thereover, means connected to said arm to swing it on its pivot and then pull it down, slots or grooves in said standard, a plate on said arm to engage with said slots or grooves, and two 110 pins secured to said standard between which said arm is moved.

8. In combination, a standard, an arm pivoted to said standard, arms secured thereto and projecting forward therefrom, an arm or 115 extension pivoted to each arm, a flexible band or chain connected to the ends of said extension, and means for moving or swinging said arm up for said curved arms to embrace and bear upon the upper side of said standard. 120

9. In combination, a standard, an arm pivoted to said standard, two arms secured thereto and projecting forward therefrom, an arm or extension pivoted to each arm, a flexible band or chain connected to the end of said extensions, a slot in said first arm, a lever pivoted to said standard, and adapted to engage with said slot for the operation of said arm. 125

10. In combination, two arms on a movable support, an arm or extension pivoted to each 130 arm, a spring secured to each former arm, bearing by its free end against the outer side of its arm extension and a plate or block centrally pivoted to each arm extension, each

plate having an outwardly-curved bearing side or face.

11. In combination, two arms on a movable support, an arm or extension pivoted to each arm, a spring bearing against the outer side of each arm extension, and a plate or block pivoted to each arm extension, each plate having an outwardly-curved bearing side or face.

10 12. In combination, two arms on a movable support, an arm or extension pivoted to each arm, a spring secured to each former arm bearing by its free end against the outer side of its arm extension, and a plate or block pivoted to each arm extension, each plate having an outwardly-curved bearing side or face.

13. In combination, a standard, an arm pivoted to said standard, two arms secured thereto, an arm or extension pivoted to each arm, a spring secured thereto, an arm or extension pivoted to each arm, a spring secured to each former arm, and bearing by its free end against the outer side of its arm extension, and a plate or block pivoted to each arm extension each plate having an outwardly-curved bearing side or face.

14. In combination, two arms on a movable support, an arm or extension pivoted to each arm, a spring secured to each former arm bearing by its free end against the outer side of its arm extension, and a series of plates or blocks pivoted to each arm extension each plate having an outwardly-curved bearing face or side.

15. In combination, two arms on a movable support, a block centrally pivoted to said arms to swing up and down and extending forward centrally between the two arms, a vertical opening in its forward end and a spring arranged to bear upon said block.

16. In combination, a standard, an arm pivoted thereto, two arms secured to said arm, a block centrally pivoted to said arm to swing up and down and extending forward centrally between the two arms, a vertical central opening in its forward end, and a spring arranged to bear upon said block.

17. In combination, a standard, a plate on the upper end of said standard, holes or openings therethrough, another plate or holder below said first plate adapted to be moved up and down in suitable guideways and provided with upwardly-projecting pins arranged to extend up into and through said holes or openings in the standard-plate when moved up thereto, an arm pivoted to said standard, a plate on its upper end and means connected to said arm to move it for its plate to be above or over said standard-plate and to be then moved down for such plate to press or bear upon said standard-plate or article placed thereon.

18. In combination, a standard, a plate on the upper end of said standard, holes or openings therethrough, another plate or holder below said first plate adapted to be moved up

and down in suitable guideways and provided with upwardly-projecting pins arranged to extend up into and through said holes or openings in the standard-plate when moved up thereto, an arm pivoted to said standard, a plate on its upper end and means connected to said arm to move it for its plate to be above or over said standard-plate and to be then moved down for such plate to press or bear upon said standard-plate or article placed thereon, said arm-plate being provided with means to receive pins on the movable plate when the latter are pressed up through the openings in the standard-plate.

19. In combination, a standard, a plate on the upper end of said standard, holes or openings therethrough, an arm pivoted to said standard, a plate on its upper end and means connected to said arm to move it for its plate to be above and over said standard-plate and to be then moved down for such plate to press or bear upon said standard-plate or article placed thereon.

20. In combination, a standard, a plate on the upper end of said standard, holes or openings therethrough, an arm pivoted to said standard having a plate on its upper end, a segment-gear on the other end of said arm, a straight or vertical extension or continuation of said gear, a rack-bar adapted to engage with said gear, a treadle connected to the rack-bar and a spring connected to the treadle and rack-bar.

21. In combination, a standard, a plate on the upper end of said standard, holes or openings therethrough, an arm pivoted to said standard having a plate on its upper end, a segment-gear on the other end of said arm, a straight or vertical extension or continuation of said gear, a rack-bar adapted to engage with said gear and means connected to the rack-bar for operation thereof.

22. In combination, a standard, a plate on the upper end of said standard, holes or openings therethrough, an arm pivoted to said standard, having a plate on its upper end, holes or openings in said arm-plate in line with the holes in the standard-plate when the arm-plate is thereover, a segment-gear on the other end of said arm and a straight or vertical extension or continuation of said gear, a rack-bar adapted to engage with said gear, a treadle connected to the rack-bar and a spring connected to the treadle and rack-bar.

23. In combination, a standard, a plate on the upper end of said standard, an arm pivoted to said standard, a segment-gear on the other end of said arm, and a straight or vertical extension or continuation of said gear, a rack-bar adapted to engage with said gear, a treadle connected to the rack-bar, and a spring connected to the treadle and rack-bar.

24. In combination, a standard, a plate on the upper end of said standard, holes or openings therethrough, another plate or holder below said first plate adapted to be moved up

and down in suitable guideways and provided with upwardly-projecting pins arranged to extend up into and through said openings in the standard-plate when moved up there-
5 to, an arm on a suitable support, a plate on one end of said arm and means connected to said arm to move it up and down and when down for its plate to press or bear upon said standard-plate or article placed thereon, and
10 holes or openings in said arm - plate corresponding to the openings in said standard-plate.

25. In combination, two arms on a movable support, and a plate or block pivoted to each arm, each plate having an outwardly-curved bearing side or face to bear against the side of the counter of a boot or shoe to hold it close to the edge of the inner sole.

26. In combination, two arms on a movable support, and a series of plates or blocks pivoted to each arm, each plate having an outwardly-curved bearing side or face to bear against the side of the counter of a boot or shoe to hold it close to the edge of the inner
25 sole.

27. In combination, a standard having its end or head suitably constructed for the heel portion of an inner sole to rest thereon and to receive the boot or shoe upper over said

end or head and for it to extend above the 30 same a short distance, an arm connected to a support adapted to be moved into position to bear or press upon the standard end or head, to hold the inner sole in position, and mechanism for pressing the upper against the 35 edge of the inner sole at the heel whereby the upper and inner sole are held in position to be afterward secured together.

28. In combination, a standard having its end or head suitably constructed for the heel 40 portion of an inner sole to rest thereon and to receive the boot or shoe upper over said end or head and for it to extend above the same a short distance, an arm connected to a support adapted to be moved into position 45 to bear or press upon the standard end or head to hold the inner sole in position, and yielding mechanism for pressing the upper against the edge of the inner sole at the heel whereby the upper and inner sole are held in 50 position to be afterward secured together.

In testimony whereof I have hereunto set my hand in the presence of two subscribing witnesses.

CHARLES W. KING.
